WILFRED CARON, OF RUMFORD, MAINE, AND PHILEAS CARON, OF AMESBURY,
MASSACHUSETTS.

COMPOUND TOOL.

1,365,658.

Specification of Letters Patent. Patented Jan. 18, 1921.

Application filed February 9, 1920. Serial No. 357,260.

To all whom it may concern:

Be it known that we, WILFRED CARON, a citizen of the United States, residing at Rumford, county of Oxford, State of Maine, and PHILEAS CARON, a citizen of the Dominion of Canada, residing at Amesbury, in the county of Essex and State of Massachusetts, have invented new and useful Improvements in Compound Tools, of which the following is a specification.

This invention relates chiefly to tools used by barbers, and is embodied in a compound tool which includes the well known tweezers, and a pick carried by the tweezers, and adapted to be inoperatively housed between the jaws thereof, and to be projected from the rigid end of the tweezers and used for purposes such as the removal of dead hairs and of concealed hairs from the faces and necks of customers, the tweezers constituting a handle whereby the pick may be manipulated.

Of the accompanying drawings forming a part of this specification,—
25 Figure 1 is a side view, on an enlarged scale, of a compound tool embodying the invention.

30 Fig. 2 is a section on line 2—2 of Fig. 1.
Fig. 3 is a section on line 3—3 of Fig. 1.
Fig. 4 is a side view of the pick.

35 Figs. 5 and 6 are views similar to Fig. 1, showing different adaptations of the tool, portions of the jaws being broken away.

Fig. 7 is a view similar to Figs. 5 and 6, illustrating the operation of reversing the pick.

The same reference characters indicate the same parts in all of the figures.

In the drawings, 12 and 13 represent 40 silent tweezer jaws, rigidly connected at one end to form a neck. As best shown by Figs. 1 and 3, the neck may be formed by interposing between the inner ends of the jaws two spacing pieces 14, which are 45 brazed, or otherwise rigidly secured to the jaws, and are spaced apart so that the neck as a whole is provided with a longitudinal aperture or passage 15, forming a guide. The free ends of the jaws normally spring

50 apart, as shown by Fig. 2. The jaw 12 is provided with a longitudinal slot 16. Slidably connected with the slotted jaw 12 is a pick 17, which is movable endwise in the slotted neck. The slotted jaw and pick are 55 provided with elements of yielding confin-

ing means for yieldingly confining the pick with its point within the aperture 15 of the neck, as shown by Figs. 1 and 2, the pick being movable endwise to project its point from the neck, as shown by Fig. 5, and enable the tweezers to serve as a handle for the pick.

One element of said confining means is a resilient metal plate or keeper 18, connected by a rivet 19 with the jaw 12, and provided 60 at its free end portion with a boss 20. The other element of said confining means is the rounded head 21 of a rivet 22 rigidly secured to the pick 17. The arrangement is such that when the pick is in the position 70 shown by Figs. 1 and 2, the boss 20 yieldably engages the head 21 and holds the pick in the position shown, the end portion of the pick being confined within the neck aperture 15, and guarded by the neck. The pick 75 is provided with ears 23, having milled edges which project from opposite edges of the pick, and outwardly from opposite edges of the jaws, and form a grip engageable by thumb and finger to move the pick relatively 80 to the tweezers.

We prefer to make the pick double-ended and reversible, one of its ends being provided with a point 17^a, and its opposite end with a hook 17^b. The keeper 18 is adapted 85 to be swung on the rivet 19, and thus displaced, as shown by Fig. 7. When the keeper is displaced the pick may be moved until its rivet 22 is at the inner end of the slot 16, so that the pick is entirely withdrawn 90 from the neck aperture 15, and is free to swing and reverse its ends and permit the end having the hook 17^b to be projected from the neck, as indicated by Fig. 6.

The apertured neck 14, and the jaws 12 95 and 13 connected thereby, constitute a body part forming tweezers, the neck constituting also a guide. The pick 17 constitutes an extension part movable in said guide and adapted by the coöperation of the headed 100 stud 21 and the longitudinal slot 16 in the jaw 12, to have an endwise and a swinging movement relative to the body part.

The arrangement is such that the extension part may be housed partly between the 105 jaws and partly in the neck, as shown by Figs. 1 and 2, so that swinging movements of the extension part are prevented, loose endwise movements of the extension part being at the same time prevented by the 110

keeper 18. The extension part may also be moved endwise to withdraw it from the neck, and then swung as indicated by Fig. 7, so that either of its ends may be projected from the neck, as shown by Figs. 5 and 6, the operation of initially swinging the extension part being facilitated by the projecting ears 23.

We claim:

- 10 1. In an article of the character described, a body part composed of resilient jaws and an apertured neck forming a guide, and connecting and spacing the jaws at one end of the body part, so that the neck and jaws 15 constitute tweezers, one of the jaws being provided with a longitudinal slot, and an extension part formed to slide longitudinally in the guide provided by the apertured neck, and having a headed stud between its ends adapted to slide and turn in said slot, the arrangement being such that the extension part may be housed partly between the jaws, and partly in the neck, turned end for end between the jaws, and 20 projected either end forward from the neck.
- 25 2. In an article of the character described, a body part composed of resilient jaws and an apertured neck forming a guide, and connecting and spacing the jaws at one end of the body part, so that the neck and jaws 30 constitute tweezers, one of the jaws being provided with a longitudinal slot, and an extension part formed to slide longitudinally in the guide provided by the apertured neck, and having a headed stud be-

tween its ends adapted to slide and turn in said slot, the arrangement being such that the extension part may be housed partly between the jaws, and partly in the neck, turned end for end between the jaws, and 40 projected either end forward from the neck, the slotted jaw being provided with a resilient keeper adapted to yieldingly engage the headed stud when the extension part is housed.

3. In an article of the character described, a body part composed of resilient jaws and an apertured neck forming a guide, and connecting and spacing the jaws at one end of the body part, so that the neck and jaws 50 constitute tweezers, one of the jaws being provided with a longitudinal slot, and an extension part formed to slide longitudinally in the guide provided by the apertured neck, and having a headed stud between its ends adapted to slide and turn in said slot, the arrangement being such that the extension part may be housed partly between the jaws, and partly in the neck, turned end for end between the jaws, and 55 projected either end forward from the neck, the extension member being provided with ears projecting in opposite directions from the jaws and forming a grip engageable by a thumb and finger.

In testimony whereof we have affixed our signatures.

WILFRED CARON.
PHILEAS CARON.
